UNITED STATES PATENT OFFICE

151,010

DESIGN FOR A CAP

Walter E. Schuessler, Chicago, Ill., assignor to Schuessler Knitting Mills, Inc., Chicago, Ill., a corporation of Illinois

Application March 31, 1947, Serial No. 138,054

Term of patent 7 years

(Cl. D3—13)

To all whom it may concern:

Be it known that I, Walter E. Schuessler, a citizen of the United States, residing at Chicago, county of Cook, and State of Illinois, have invented a new, original, and ornamental Design for a Cap, of which the following is a specification, reference being had to the accompanying drawing, forming a part thereof, in which:

Figure 1 is a side view in elevation of a cap, showing my new design; and Fig. 2 is an edge view in elevation.

The side opposite that shown in Fig. 1 contains the same showing. The animal representation is lined to indicate color contrast only.

I claim:

The ornamental design for a cap, as shown and described.

WALTER E. SCHUESSLER.
